UNITED STATES PATENT OFFICE.

CHARLES S. LOCKWOOD, OF NEWARK, NEW JERSEY, ASSIGNOR TO HYATT ROLLER BEARING COMPANY, OF HARRISON, NEW JERSEY, A CORPORATION OF NEW JERSEY.

PRESSED-STEEL HANGER-BOX.

1,107,677.

Specification of Letters Patent. Patented Aug. 18, 1914.

Application filed February 19, 1914. Serial No. 819,674.

To all whom it may concern:

Be it known that I, CHARLES S. Lockwood, a citizen of the United States, residing at 289 Market street, Newark, county of 5 Essex, and State of New Jersey, have invented certain new and useful Improvements in Pressed-Steel Hanger-Boxes, fully described and represented in the following specification and the accompanying drawings, forming a part of the same.

The object of this invention is to furnish a cheap and strong construction for a roller-bearing hanger-box whereby the parts may be made wholly of sheet-metal drawn or 15 pressed to shape, and the box may be provided with opposite parallel hanger-guides adapted to guide the box between the cheeks of the hanger. With this construction, the shell of the hanger-box is formed of a cylindrical drawn steel tube the inner wall 20 of which is smooth enough, without any finish, to support the rolls in their rotation around the shaft or axle which is supported in the box.

25 The opposite hanger-guides are formed upon a sheet-metal saddle pressed into such shape as to form seats upon the upper and lower sides of the box with sockets to receive the points of adjusting-screws, braces 30 projected from the seats toward the opposite ends of the shell and wings projected from the sides of the seats toward the center line of the shell where they contact with one another and with the shell. The saddles 35 are secured to the shell by electric spot-welds or by riveting. A collar is bent inwardly upon one end of the shell and a sheet-steel cap forming a similar collar is pressed elastically upon the opposite end. With this 40 construction, a single sheet-steel tube from the entire body of the box as well as the cylindrical seat within which the rolls revolve, and such shell requires no casing or exterior support other than that afforded by the saddles.

45 Spring-wipers may be inserted in the bottom of the shell at its opposite ends to press upon the shaft or axle, and wipe off any lubricant, and thus prevent it from exuding 50 at the ends of the box. Such wipers require no adjustment when in use, nor any projections upon the outer sides of the box.

The wipers are supported movably in sockets, and each socket is secured to the

adjacent collar at the end of the shell, and 55 each socket carries within the shell a transverse guard which serves to hold the cage containing the rolls from longitudinal movement in the shell.

The invention will be understood by reference to the annexed drawing, in which—

Figure 1 is a plan of the hanger-box with sections of the hanger-legs which form the cheeks between which the hanger-box is 60 movably supported; Fig. 2 is a perspective view of the cap for one end of the sleeve; Fig. 3 is an elevation of the box, the right-hand end showing the exterior of the box, and the left-hand end showing the shell and saddles in section; Fig. 4 is a cross section 65 at the center line of the box; Fig. 5 is a side view of one of the saddles detached from the box; and Fig. 6 is an end view of the box; and Fig. 7 shows the saddle made in one piece. 75

a designates the shell, formed of a cylindrical drawn steel-tube with a collar *b* spun inwardly upon one end. At the opposite end the cap is provided with a similar collar *c* and a cylindrical flange *d* which fits tightly 80 over the end of the shell so as to be pressed thereon and held by friction.

A set of rolls *e* carried by a cage *e'* is fitted to revolve in contact with the inner wall 85 of the shell and with guards inside the shell.

In forming the saddles by stamping from sheet-steel, it can embrace the whole, or only one-half of the shell, and each side is constructed with a central seat *g* having a socket *h* in the middle to receive the point of an 90 adjusting screw *h'*, with integral braces *i* projected from the seat toward the opposite ends of the shell and having cylindrical curvature to fit the same, and with wings bent to fit the opposite sides of the shell and to 95 contact with the shell and preferably with one another, upon its center line. The saddle when thus adjusted upon the shell is secured thereto by rivets or by spot-welds effected electrically at the points marked *l*. 100

Spot-welds are preferable, as the inner surface of the shell must be kept entirely smooth to form a cylindrical seat for the rolls, and the use of rivets would necessitate perforation of the shell and the hammering of the rivets, whereas spot-welds do not cause any perforation nor deform the shell 105 in any way.

The wings are shaped in the stamping operation to form parallel hanger-guides *k* at opposite sides of the shell across its center line, and one of such guides is formed with 5 a rib *k'* which extends across the center line of the shell and is adapted to fit a groove *m* in one of the cheeks of the hanger, when the box is fitted between the legs *n* of the hanger, as indicated in Fig. 1.

16 By forming the saddle of pressed sheet-steel it is made lighter and cheaper than cast-metal, and not only possesses a more accurate form but much greater strength than cast-metal of the same weight, and such 15 saddles are readily secured to the shell without perforating the latter, by welding there-to at various points by an electric current, applied through electrodes upon the inner side of the shell and upon the outer side of 20 the saddle. The shell thus possesses an unbroken cylindrical wall upon its interior which is well adapted to support the rolls as they rotate about the shaft.

The wipers, to confine the lubricant to the 25 shell, are shown as blocks *o* fitted to move radially in sockets *p* which are secured by welding, or otherwise, to the collars *b* and *c* at the ends of the shell, and each socket has a segmental guard *q* attached to its inner 30 side which serves as a guide for the cage *e'*, and thus holds the set of rolls from longitudinal movement in the shell.

The wiper-blocks *o* are pressed constantly toward the shaft *s* by springs *r* within the 35 sockets *p*, and operate to wipe off any oil that moves toward the end of the shell and thus confine it therein.

By attaching one of the wipers and guards *q* to the cap, it is removable from the shell 40 with the cap, so that the rolls and their cage can be inserted within the box, and thereafter held in place by such removable guard.

If desired, the saddle may be made in one 45 piece of sheet-metal, as shown in Fig. 7, with the seats *g* stamped thereon, the wings *i* curved to fit the shell *a*, and the hanger-guides *k* also stamped to fit the outside of the shell, the whole being capable of bending 50 at four places marked 1, 2, 3, 4, so as to embrace the entire circumference of the shell.

The construction described herein is especially adapted for use in cases where the shaft can be inserted in the box, or the box 55 slid upon the end of the shaft longitudinally.

Where the shell is formed of an unbroken cylinder, it has much greater strength than a divided shell, and the use of guides and fastenings for holding divided parts together 60 when in use is wholly avoided.

Hanger-boxes for such a use can, by this construction, be made very cheaply, and per-

fectly adapted to the uses of a roller-bearing.

Having thus set forth the nature of the 65 invention what is claimed herein is:

1. A pressed sheet-metal hanger-box having a shell consisting of a cylindrical undivided drawn steel tube, pressed sheet-metal saddles secured upon its opposite sides and 70 shaped to form opposite parallel hanger-guides, and a set of rolls fitted to revolve upon the inner wall of such shell.

2. A pressed sheet-metal hanger-box having a roll-supporting shell consisting of a 75 cylindrical undivided drawn tube with pressed sheet-metal saddles fitted to its upper and lower sides and formed with parallel hanger-guides at opposite sides, such 80 guides contacting with the shell at its opposite sides and attached thereto by suitable means, and a set of rolls fitted to turn upon the inner wall of such shell.

3. A pressed sheet-metal hanger-box having a roll-supporting shell, consisting of a 85 cylindrical undivided drawn steel tube with pressed sheet-metal saddles fitted to its upper and lower sides and each provided with a central seat having a socket to receive an adjusting-screw, integral braces projected 90 from such seats toward the opposite ends of the shell, and integral side wings projected from such seats and forming parallel guides at opposite sides of the shell, such saddles being secured to the shell by suitable means. 95

4. A pressed steel hanger-box having a roll-supporting shell consisting of a cylindrical undivided drawn steel tube with a collar bent inwardly at one end and having a pressed steel cap fitted elastically upon the 100 opposite end, sheet-metal sockets for spring oil-wipers secured within the ends of the shell by spot-welds, spring wiper-blocks fitted movably to such sockets, and sheet-metal saddles fitted to the upper and lower 105 sides of the shell and secured thereto by spot-welds so as to form no break in the bearing-surface for the rolls.

5. A pressed steel hanger-box, having a roll-supporting shell consisting of a cylindrical undivided drawn steel tube provided with a saddle formed in one piece of sheet-metal with parallel hanger-guides at opposite sides and such guides contacting with the shell at opposite sides and secured 115 thereto by suitable means.

In testimony whereof I have hereunto set my hand in the presence of two subscribing witnesses.

CHARLES S. LOCKWOOD.
